UNITED STATES PATENT OFFICE.

JEAN SÉNÉGAS, OF NEW YORK, N. Y.

MEANS FOR SUPPORTING AUXILIARY HAIR.

Application filed March 12, 1925. Serial No. 14,861.

To all whom it may concern:

Be it known that I, JEAN SÉNÉGAS, a citizen of the United States, and a resident of the borough of Manhattan, city, county, and State of New York, have invented certain new and useful Means for Supporting Auxiliary Hair, of which the following is a specification sufficient to enable those skilled in the art to which the invention appertains to utilize the same.

The object of my invention is to provide simple, inexpensive but effective and conveniently manipulatable means for feminine use whereby artificial or auxiliary hair strands may be applied to and supported at the back of the head of the user to compensate for shortness or insufficiency of natural growth, and particularly for use in conjunction with bobbed hair when it is desired to conceal the lower ends thereof.

To this end my invention consists essentially of an elastic resilient straddle band adapted to fit the rear portion of the head of the wearer and provided with ear hooks for sustaining it in position and also adapted for the attachment of auxiliary strands of hair, all as hereinafter fully set forth,—an incidental feature being the adjustability of the hook ends of the device whereby it may be made to conform to different cranial dimensions.

In the accompanying drawings I illustrate a practical application and embodiment of the essential features of my invention, although I do not wish to restrict myself to the identical construction and configuration of parts herein shown by way of exemplification, since changes in minor details, and equivalent mechanical expedients, may be resorted to with like results, and without departing from the spirit and intent of my invention in this respect.

With this understanding:—

Fig. 1, represents a rear view of the head of a wearer of my straddle band, the latter being shown in position thereon, but without the auxiliary hair strands;

Fig. 2, is a similar view, showing the auxiliary hair strands in position as supported on the straddle band;

Fig. 3, is a detail view of possible hair strands adapted for use in conjunction with my straddle band;

Fig. 4, is a profile view of the head of a

wearer, more or less diagrammatic, illustrating the function of the ear hooks the auxiliary hair strands being omitted;

Fig. 5, is a perspective view of a one piece structure of my straddle band;

Fig. 6, is a detail view of one end of my straddle band, illustrating one method of providing for the adjustment of an ear hook thereon;

Figs. 7 and 8, are detail views illustrating another method of adjustably supporting an ear hook on the medial portion of the band.

I prefer to make my straddle band B, of elastic resilient material of relatively light flexible character, the medial portion b, being somewhat wider than the side members b', b', which terminate in ear hooks h, h, each adapted to fit over the helix of an ear of the wearer as indicated more particularly in Fig. 4, of the drawings.

The straddle band B, is formed with perforations a, a, or otherwise adapted to the adjustment and support of auxiliary hair strands S, of any suitable or desired character,—those shown in Figs. 2 and 3 being illustrative only of the function of the device, which is primarily to cover and conceal short hair at the back of the head with a screen of supplementary hair corresponding in appearance with the natural growth of hair on the head of the wearer of said straddle band B. Hence, obviously, the braiding or weaving of the auxiliary hair strands S, is subject to variation to suit requirements or preference.

The perforations a, a, are adapted to facilitate the attachment of the hair strands S, to the back or medial portion b, of the straddle band B, by resort to stitching or the like, although the means of attachment of the auxiliary hair S, to the straddle band B, is not material provided ample support is afforded said screen of hair S.

The set or normal configuration of the straddle band B, is curvilinear, substantially as illustrated in Fig. 5, of the drawings, so as to conform in general outline to the rear portion of the cranium of the wearer, the side members b', b', with the medial portion b, constituting, essentially, a straddle clasp which is enhanced in function by the elastic resilient character of the material used in the formation of said

straddle band B, considering it in a unitary sense, so that the band will fit snugly around and against the ends of the natural growth of hair on the head and confine 5 same to the base of the skull.

In order, however, to insure positive support for the straddle band B, and its screen of auxiliary hair S, I provide the ends of the side members b', b', with the aforesaid 10 ear hooks h, h, by means of which the device may be suspended, as it were, in position on the lower posterior portion of the head of the wearer, as will be understood by reference more particularly to Fig. 4, of 15 the drawings.

Furthermore, to adapt my straddle band to the varying requirements of use, as to 20 cranial size and extent of hair ends to be confined thereby, I attach the shanks h', h', of the ear hooks h, h, to the medial portion b, of the band B, by means which admit of the adjustment of said hooks h, h, on the side members b', b', of the band. Thus in 25 Fig. 6, inturned lugs h², h², on the shank h', of the hook h, clasp the side member b', of the band B, so that the hook is slidably supported on said side member b', whereas a similar adjustable attachment may be 30 effected by means of holes a', a', in the

overlapping parts as provided for in Figs. 30 7 and 8, of the drawings.

While my straddle band B, and its screen of hair strands S, may be used for supplementary embellishment of hair coiffure the combination device thus attained is especially useful and effective in covering short hair of the bobbed style when it is desired to camouflage the "bob" cut. 35

What I claim as my invention and desire to secure by Letters Patent, is:— 40

1. As an article of manufacture, a straddle band of the character designated, formed with ear hooks and having means to support strands of auxiliary hair, substantially in the manner and for the purpose 45 set forth.

2. As an article of manufacture, an elastic resilient straddle band of the character designated, formed with ear hooks and with perforations for the support of strands of 50 auxiliary hair, substantially in the manner and for the purpose set forth.

3. As an article of manufacture a straddle band of flexible material having wide median portion and narrow ends, and hooks 55 at the ends, said wider portion having perforations for the attachment of hair.

JEAN SÉNÉGAS.
